UNITED STATES PATENT OFFICE.

ABEL L. BROWNRIGG, OF EAST ORANGE, NEW JERSEY, ASSIGNOR TO FENTON R. BYDLE, OF JAMAICA, NEW YORK.

COMPOSITION SHINGLE.

Application filed February 7, 1925. Serial No. 7,533.

This invention relates generally to shingles of the composition type and more particularly relates to the provision of suitable anchoring construction for shingles of this general type.

Shingles of this type are usually laid in a diagonal position, that is, with the corners of a substantially square shingle extending in horizontal and vertical directions so that the lower portion of the shingle which is exposed to the weather is bounded by downwardly converging lateral edges. In order to anchor the lowermost corners of such shingles to the underlying shingles, it has been the practice to fold the corner of the shingle to lie underneath the body portion and to thread through or secure to the undrawn portion a separately formed bar or strip of metal or other suitable material having projecting ends.

A general object of the present invention is to provide a shingle having an anchoring device consisting of a single integral undrawn corner or tab member which affords laterally extending wing portions or edges adapted to perform the function of interlocking with adjacent shingles so as to hold the downward end of the shingle in place.

Another object of the invention is to provide a shingle of the interlocking type in which a square shingle blank is used without waste, and yet the bent under tab is arranged to interlock with adjacent shingles.

The invention consists of a shingle provided with an undrawn corner tab member bent on a line of fold which does not extend wholly across the shingle but terminates at each end at points spaced from the lateral edges of the shingle. This provides a tab member having an intermediate portion of greater width than the portion at the line of fold and, in addition, provides downwardly projecting tip members in the body of the shingle at each end of the line of fold of the corner tab member. With this arrangement the downwardly extending and laterally separated tip members referred to extend along the edge portions of the adjacent underlying shingles and serve as guide members in the placing of each shingle in proper superposed relation to the underlying shingles. Other useful results of this construction reside in the elimination of horizontal edge portions in the uppermost shingles which extend laterally from the inclined

edges of the underlying shingles and provide a way for wind driven rain to find its way beneath the shingles. Also the presence of the tip members tends to resist wind forces in that the pointed terminals of the tip members cannot readily be engaged and lifted by wind so that a secure and impervious roof construction is thereby provided.

In the drawings, in which a preferred embodiment of the invention has been selected for illustration,

Figure 1 is a plan view of a shingle embodying the invention and showing a corner tab portion before it has been folded.

Figure 2 is a view similar to Figure 1 showing the corner tab portion of the shingle in its undrawn position.

Figure 3 is a view taken in section along line 3-3 of Figure 2.

Figure 4 is a plan or face view of a group of shingles, such as is shown in Figure 2 in assembling relation on a roof, or the like.

Figure 5 is a fragmentary view showing a modified form of the invention.

Referring to the drawings for a more detailed description of the invention, a shingle 10 is shown which has a substantially square outline and is formed of any suitable composition, such as asphaltum-impregnated fibrous material. Such shingles are characterized by a certain degree of flexibility which renders it desirable to provide for securely anchoring the lowermost margin of the shingles beneath the edges of adjacent previously laid shingles. It is the usual practice to lay shingles of this type in a diagonal position, that is, with the corners extending horizontally and vertically, the lowermost corner being arranged to support an anchoring device or to itself provide an undrawn anchoring tab member.

In the present invention, a pair of short cuts or slits 11 are formed in oppositely disposed relation in the opposite edges of the shingle adjacent to the lowermost corner portion 12. The slits 11 are formed substantially at right angles or perpendicularly to the side edges of the shingle and the intervening corner tab portion 12 is then bent underneath the shingle along the line of fold 13 extending between and connecting the inner extremities of the slits 11.

With this arrangement it will be seen that a tab member 12 is formed and which has laterally extending wing portions 14 which

serve in practice to be placed in anchoring position beneath the edges of adjacent shingles 10', as is clearly shown in Figure 4 of the drawing.

- 5 Not only is a desirable anchoring device thus provided which can be placed in interlocking engagement with two underlying shingles, but the placing of the slits 11 in the position and in the direction shown 10 provides a pair of downwardly extending tip members 15 on the body portion of the shingle and at the opposite extremities of the line of bend 13 on which the tab member 12 is folded. The tip members 15 provide a 15 number of useful functions in that they extend along upper surfaces of the marginal portions of the adjacent underlying shingles 10' and thereby obviate a horizontal edge which has heretofore been presented in 20 shingles heretofore known and used and which has afforded a means of entry for rain driven by wind to find its way back of the line of fold of the undeturned tab members heretofore used.
- 25 Another advantage of the downwardly extending tip portions 15 resides in the resistance which they offer to the engagement of the shingle by wind forces tending to lift the lower extremities of the shingles from 30 their position. Still another advantage resides in the guiding or directing function which is provided by the tip portions to insure the correct position of the uppermost shingle with the two underlying shingles on 35 which it is laid. The tip members 15 also assist in the holding of the engaged portions of the adjacent shingles 10' against the underlying surfaces on which they are laid.

In covering the surfaces with shingles of 40 the type described, the tip portions 12 are folded to their undeturned position and each shingle is then forced upwardly into position into the angle formed by the converging edges of the adjacent shingles 10', 45 so that the undeturned tab portion 12 is pulled upwardly beneath the contiguous corners of the adjacent shingles 10' to thereby interlock the newly laid shingle with the two shingles previously laid.

50 Not only is an effective interlocking action produced by the anchoring engagement of the tab member 12 beneath the side edges of the adjacent shingles 10' but the presence of the downwardly extending tip members 15 produces a self-spaced or self-alinement of the shingles which does away with the necessity for using a chalked cord or other device for establishing a new alinement for the uppermost corner portions of the shingles 55 in the laying operation. In other words, the frequent aligning operations made necessary in the laying of shingles of previously known types is done away with by the self-spacing function that is provided by the guiding or 60 directing tip members 15 at the lower ex-

tremities of the shingles. It will be seen that the fitting of these angular tip members to the angularly disposed edges of the adjacent shingles 10' automatically brings about the correct placement or positioning of the shingle whereby the spacing or alinement of the shingles with relation to each other is invariably accomplished.

65 In order to secure the shingles in place the nails 16 may be made use of, preferably two nails being used adjacent each lower edge of each shingle. It will be seen that the nails are not driven through the tab members, the object of this being to permit limited play or movement of the lower tab portions of the shingles to obviate the tendency to buckle which would be produced under the expansion of the main body of the shingle by the action of the heat of summer temperatures.

70 In a modified form of the invention shown in Figure 5 of the drawing the pointed tip on the end of the tab member is dispensed with and an elongated edge 17 made use of. This form of tab member is more readily 75 placed in position than the tab member having the pointed tip portion and in many circumstances the use of this type of tab member is to be preferred.

75 What I claim is:—

1. A shingle having its lower portion formed with downwardly converging side edges, said shingle having two laterally spaced apart downwardly projecting tip members at its lower extremity, and an undeturned tab member folded on a line connecting the base portions of said tip members.

2. A shingle having its lower portion formed with downwardly converging side edges, said shingle having two laterally spaced apart downwardly projecting tip members at its lower extremity, and an undeturned tab member folded on a line connecting the base portions of said tip members and having a portion of greater width than the width of the tab at the folded line.

3. A shingle having its lower portion formed with downwardly converging side edges, said shingle having two laterally spaced apart downwardly projecting tip members at its lower extremity, and an undeturned tab member folded on a line connecting the inner base portions of said tip members, and said tab member having laterally extending corner portions.

4. A shingle having a lower portion formed with downwardly converging side edges and provided adjacent the lower extremity with oppositely disposed slits extending inwardly at right angles to the edges to provide a corner tab portion with laterally extending corner portions, said tab member being undeturned to a position in which the laterally extending corner por-

tion will underlie the edges of adjacent shingles and the said edges of the lower portion of the shingle being located beyond the corner portions of the tab member 5 whereby to cause the edges of the shingle to overhang the tab member.

5. A shingle provided with oppositely disposed slits extending inwardly substantially at right angles to the opposite edges of 10 the shingle adjacent the lowermost corner portion thereof, and said corner portion being turned under the shingle on a line of fold extending between the inner ends of the slits, whereby downwardly projecting tips are provided on the shingle at the opposite ends of the line of fold of the underturned corner tab member.

6. A shingle of the flexible composition type having a downwardly extending corner

portion, said downwardly extending portion 20 being provided with oppositely disposed slits extending inwardly at right angles to the edge, and the tab member thereby provided being undeturned to provide laterally extending anchoring members spaced inwardly 25 from the edges of the overlying body of the shingle.

7. A shingle of the flexible composition type having a downwardly extending corner portion, said downwardly extending portion 30 being provided with an undeturned tab member having laterally extending portions arranged to underlie adjacent shingles, and extensions on the lower extremity of the shingles arranged to overlie the adjacent 35 shingle edges to anchor them in position.

ABEL L. BROWNRIGG.
